DISPLAY CABINET

Charles W. Boston, Kenmore, N. Y.

Application May 8, 1933, Serial No. 669,985

7 Claims. (Cl. 211—71)

This invention relates to cabinets for storing and displaying articles, and it has particular relation to storage or display cabinets in which a plurality of displaying arrangements are possible as well as being selectively interchangeable depending upon the kind of goods to be stored or displayed, or upon the type of shelf arrangement of the cabinet desired.

In business concerns engaged in selling merchandise of various kinds, for example, groceries wherein various types of goods are handled, it is very important that the goods should be displayed to best advantage. Especially in grocery stores there is considerable amount of business in so-called package goods and also in so-called bulk goods. Often it happens that the same class of goods is sold in both package and bulk form and the demand for both forms varies from time to time.

One of the principal objects of the invention is to provide a cabinet which is adapted to display both package and bulk goods, and which is readily convertible for displaying either package or bulk goods, or part package and part bulk goods.

Another object of the invention is to provide a convertible display cabinet that is provided with interchangeable or reversible parts for displaying various types of goods without resorting to the use of fastening devices, tools, or the like, and that can be converted simply and effectively at a moment's notice by extremely simple operations.

In the drawings:

Fig. 1 is a vertical section of a display cabinet embodying the invention;

Fig. 2 is a front elevation of a display cabinet;

Fig. 3 is a fragmentary perspective illustrating details of construction of the cabinet; and

Fig. 4 is a diagrammatic perspective of a metal shelf.

In practicing the invention a framework 10 is provided which comprises end frame members or walls 12, rear wall structure 15 connecting the end walls, and other frame members 16 which serve to brace and strengthen the entire cabinet structure.

It will be observed that the front edges 17 of the end walls 12 are inclined rearwardly from the bottom portion of the cabinet, and that permanent shelves 18 having suitable mounting supports 19 secured upon the end walls, are horizontally arranged and extend substantially to the front of the cabinet. Other cabinet shelves 20 also are arranged horizontally but extend for-

wardly only to intermediate locations between the rear wall 15 and the front edges on the walls 12.

Sets of guides 22 are provided in the end walls 12 and each set includes a substantially horizontal guide portion 23 and an inclined guide portion 25 which intersect substantially at or adjacent the front edge of the wall 12 in a guide entrance portion 26. Removable and reversible shelves 27 are mounted in the guides 22 by inserting opposite ends 28 of each shelf slidably into opposed portions of the guides in opposite end walls 12, and opposite ends of each reversible shelf are adapted to be guided into opposed entrance portions 26 and then directed either into opposed guide portions 23 or into the opposed guide portions 25. In referring to a set of guides, it is intended that one set should include each group of three intercommunicating groove sections 23, 25 and 26 of one end wall 17, and it requires two of such sets of guides to support each shelf 27 in a plurality of positions; that is, one set in one wall 12 and another set in the opposite wall 12 at opposite ends of the shelf.

One edge of each shelf 27 rigidly or integrally carries a display member 29 which has an inclined face 30 disposed at substantially the same inclination as the front edges 17 of the end walls when the shelf is in a horizontal position in the horizontal guide portion 23 of the wall. Thus, uniform and proper cooperation of the shelf and cabinet walls is insured. Guide flanges or recesses 31 in a guide member 32 that is secured upon the face of the member 29 are adapted to slidably receive plates 33 to serve as price tags or name plates for whatever data it is desired to be applied thereon. Similar plate holding structure 34 is applicable in substantially the same manner to the front portions of the permanent shelves 18.

In this arrangement of the members the permanent shelves 18 and reversible shelves 27 are aligned to provide substantially continuous shelf surface upon which package goods 35 are especially adapted to be displayed and stored. The shelves are of such depth that suitable space is provided for storing in the rear portion of the cabinet and the front edge or display member 29 insures proper aligning arrangement of the packages to be displayed.

The other edge of the reversible shelf 27 is provided with a rabbeted edge portion 36 to receive an anchoring means 37 in the form of a plate bent into substantially channel form for engaging a flange 38 of a carton display cover 39.

that is adapted to be mounted upon an open end of a carton 40 for containing bulk merchandise. When a carton of this kind is displayed the shelf 27 is inserted into the guide portion 25 to present the shelf at an angle to the horizontal, and to present the anchoring means 37 at the front of the cabinet for engagement with the carton cover flange. In this arrangement the carton cover 39 is disposed at the proper angle to the cabinet, 10 that is, substantially the same inclination as the inclination of the front edges 17 of the end walls. When each reversible shelf 27 is in this position there is sufficient space in the rear of the cabinet for storing other cartons, or the like, upon the rear shelf 28 and these cartons can be used when the contents of the front or displaying cartons and covers are exhausted.

From this description it will be apparent that the cabinet is adapted for immediate change for displaying package or bulk merchandise, merely by removing and reversing any or all of the shelves 27, according to the amount of space desired for each type of goods. Although only a portion of the cabinet is shown to be provided with reversible shelves, it is apparent that this type of shelf can be applied for utilizing the entire capacity of the cabinet. Grooves have been shown as providing a simple means for properly guiding and supporting the shelves in the end walls. However there are other types of guides which could be employed for achieving the same results. At the bottom portion of the cabinet one of the members 16 is shown as being mounted at an incline corresponding to the inclination of the inclined guides 25 and is adapted to receive one of the cartons 40 in the same manner as the shelf 27 when the latter is mounted in the guide 25.

In Fig. 4 a shelf 50 is shown which is composed of suitable sheet metal and the opposite edge portions of the shelf are provided with a tag holding channel 52 and carton flange engaging members 53 corresponding substantially to the member 29 and anchoring means 37, respectively, described with reference to Figs. 1 and 3. One edge of the shelf 50 is provided with a reinforcing flange or bead 55 and the other edge portion has a portion welded or otherwise secured, as indicated at 56, to the rear surface of the channel 52. End portions 57 are adapted to fit into guides of the type shown in Figs. 1 and 3 or special metal cabinets can be made to provide a complete metal assembly.

Although only two forms of the invention have been shown and described in detail it will be apparent to those skilled in the art that the invention is not so limited but that various changes may be made therein without departing from the spirit of the invention or from the scope of 60 the appended claims.

I claim:

1. A display cabinet comprising a framework having permanent shelves therein, sets of guides having guide portions aligned with one of the shelves and having guide portions disposed at angles to said shelves, and a removable and reversible shelf mounted in said guides and adapted to be positioned either as a continuation of the permanent shelf or as a shelf disposed at an angle to the permanent shelf depending upon the direction of insertion of the reversible shelf into the guides.

2. A display cabinet comprising a supporting framework having front and rear portions, a plurality of pairs of opposed guides provided in

the framework, one pair of guides being disposed at an angle to another pair, a shelf removable and reversible with respect to the framework to present either of two of its opposite edges at the front of the framework, said shelf having means 5 cooperable with either of the pairs of guides to support the shelf in any of a plurality of positions depending upon the pair of guides into which the shelf is inserted.

3. A display cabinet comprising a supporting framework having front and rear portions, a plurality of pairs of opposed guides provided in the framework, one pair of guides being disposed at an angle to another pair, a shelf reversibly disposed with respect to its opposite edges in 15 the framework to present either of two of said opposite edges at the front of the framework, said shelf having means cooperable with any of the pairs of guides for insertion of the shelf into the supporting framework in either of a 20 plurality of positions depending upon the pair of guides into which the shelf is inserted, means at one edge of the shelf for alining one type of merchandise upon the latter at the front of the framework in one position of the shelf, and 25 means at the opposite edge of the shelf for alining another type of merchandise upon the latter at the front of the framework in the reversed position of the shelf.

4. A display cabinet comprising a supporting framework having front and rear portions, a plurality of sets of guides in the framework, the guides of each set being disposed at an angle to each other and converging to form a single shelf receiving entrance adjacent the front of the framework, a shelf removable and reversible for support in said sets of guides, said sets of guides being formed to receive the shelf in a plurality of 30 selective positions depending upon the angle at which the shelf is inserted into the guides, opposite edges of the shelf having display positioning means adapting the shelf for displaying different types of goods, means included in the shelf for 35 slidably mounting the latter in any of the guides at the front of the framework.

5. A display cabinet comprising a supporting framework having front and rear portions, a plurality of pairs of opposed guides provided in the framework and converging to provide shelf receiving entrances at the front of the cabinet, a shelf removable and reversible with respect to the framework and normally presenting one or the other of its opposite edges at the shelf entrance 50 of the front of the cabinet, said shelf having means cooperable with any of the pairs of guides to support the shelf in any of a plurality of positions depending upon the angle at which the shelf is inserted into the guides.

6. A display cabinet comprising a supporting framework having front and rear portions, a plurality of pairs of opposed guides provided in the framework, one pair of guides being disposed at an angle to another pair, and converging toward 65 the front of the cabinet to form common entrances for the pairs of guides, a shelf removably and reversibly disposed in the framework to present either of two of its opposite edges at the guide entrances of the front of the cabinet, said shelf having means cooperable with any of the pairs of 70 guides for insertion of the shelf into the supporting framework in any of a plurality of positions depending upon the angle at which the shelf is inserted into the guides, means at one edge of 75 the shelf for aligning one type of merchandise

upon the latter at the front of the framework in one position of the shelf, and means at the opposite edge of the shelf for aligning another type of merchandise upon the latter at the front of the framework in the reversed position of the shelf.

7. A display cabinet comprising a supporting framework having front and rear portions, a plurality of sets of shelf supporting guides incorporated in the framework, guides of one set being disposed at an angle to guides of another set, a shelf reversibly and removably supported by the

framework and insertable into any of the sets of guides in a plurality of selective positions depending upon the guides selected to receive said shelf, opposite sides of the shelf having different forms of display facilitating means adapting the shelf for displaying different types of merchandise, and means included in said shelf for slidably mounting the latter in any of the guides with either of said opposite edges presented at the front of the framework.
